CLAIM

The ornamental design for a camera housing, as shown and described.

DESCRIPTION

FIG. 1 is a front, top, and right side perspective view of a camera housing showing our new design according to a first embodiment;

FIG. 2 is a front, bottom and left side perspective view thereof;

FIG. 3 is a back, top, and left side perspective view thereof;

FIG. 4 is a back, bottom, and right side perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.
